UNITED STATES PATENT OFFICE.

JOSEPH FORMAN, OF WALBROOK, MARYLAND.

BUTTONHOLE-SEWING MACHINE.

1,269,416.

Specification of Letters Patent. Patented June 11, 1918.

Application filed May 18, 1916. Serial No. 98,411.

To all whom it may concern:

Be it known that I, JOSEPH FORMAN, a citizen of the United States, residing at Walbrook, State of Maryland, have invented certain new and useful Improvements in Buttonhole-Sewing Machines; and I do declare the following to be a full, clear, and exact description of the invention, such as will enable others skilled in the art to which it appertains to make and use the same.

This invention relates to buttonhole sewing machines and more particularly to the type designed for producing buttonholes having an eye at one end thereof.

15 The main object of the invention is to provide a simply constructed machine of this character employing a single thread and forming a stitch identical with the buttonhole stitch made by hand and which may 20 be operated by unskilled workmen, the present invention being an improvement on the machine shown and described in my co-pending application, Serial No. 29372, filed May 20, 1915.

25 Another object is to provide improved means for gripping and releasing the needle and for transferring it from one needle bar to the other.

Another object is to provide simple and 30 efficient means for reciprocating the needle bars.

Still another object is to provide an improved thread tightening and tension mechanism for preventing the thread from becoming entangled during the operation of 35 the machine and which is so constructed that all danger of the thread being broken thereby is avoided.

Still another object is to provide an improved stitch setting mechanism.

With these and other objects in view, the invention consists of certain novel features of construction and the combination and arrangement of parts as will be hereinafter 45 more fully described and claimed.

In the accompanying drawings:

Figure 1 represents a side elevation of a machine constructed in accordance with this invention, the work table thereof being 50 shown in section;

Fig. 2 is a central longitudinal vertical section thereof;

Fig. 3 is a front elevation thereof with the parts shown in the position assumed 55 when transferring a needle from the upper needle bar to the lower;

Fig. 4 is a transverse vertical section taken on the line 4—4 of Fig. 1;

Fig. 5 is a horizontal section taken substantially on the line 5—5 of Fig. 1; 60

Fig. 6 is a similar view taken substantially on the line 6—6 of Fig. 1;

Fig. 7 is an enlarged detail front elevation of the upper needle bar showing the needle gripping and releasing mechanism; 65

Fig. 8 is a side elevation with the front plate of the housing removed, the depressing mechanism for the housing being shown partly in section;

Fig. 9 is a similar view partly in section 70 showing the connection of the jaws with the needle bar;

Fig. 10 is a side elevation taken in a plane at right angles to Fig. 7;

Fig. 11 is a vertical section taken on the 75 line 11—11 of Fig. 8;

Fig. 12 is an edge view and a front elevation respectively of one of the needle gripping jaws;

Fig. 13 is a similar view of the other jaw; 80

Fig. 14 is a horizontal section taken on the line 14—14 of Fig. 7;

Fig. 15 is a similar view taken on the line 15—15 of Fig. 8;

Fig. 16 is an enlarged detail plan view 85 of the loopers shown in closed position and with the actuating lever thereof broken off;

Fig. 17 is a similar view with the looper jaws shown in open position;

Fig. 18 is a similar view partly in section; 90

Fig. 19 is a longitudinal section taken on the line 19—19 of Fig. 16;

Fig. 20 is a front elevation of the loopers shown in closed position;

Fig. 21 is a transverse section taken on the line 21—21 of Fig. 18; 95

Fig. 22 is a horizontal section taken on the line 22—22 of Fig. 20;

Fig. 23 is a fragmentary plan view of the work table partly in section and with the 100 cloth plate removed to disclose the location of the feed wheel;

Fig. 24 is a horizontal section taken substantially on the line 24—24 of Fig. 1 and directly under the work table; 105

Fig. 25 is a similar view taken on the line 25—25 of Fig. 1;

Fig. 26 is a detail horizontal section taken on the line 26—26 of Fig. 2;

Fig. 27 is a similar view taken on the line 110 27—27 of Fig. 2;

Fig. 28 is an enlarged detail perspective

view showing the stitch forming mechanism in the position assumed at the completion of a buttonhole;

Fig. 29 is a similar view showing the 5 needle in the act of ascending;

Fig. 30 is a similar view showing the needle passing downwardly through the cloth and ready to enter between the loopers;

Fig. 31 is a similar view showing the 10 needle after it is passed through the cloth and with the tension device ready for operation;

Fig. 32 is a similar view showing the 15 tightening device in its outward movement for tightening the thread and engaging it with the tension or thread holding device;

Fig. 33 is a plan view showing the cloth 20 clamped in operative position with a piece of cloth clamped thereby and with the buttonhole formed therein stretched ready to be stitched;

Fig. 33^a is an enlarged detail of the cloth having the buttonhole cut ready for stitching;

Fig. 34 shows a view similar to Fig. 33 with the clamp omitted with the exception of its pin which is shown in section;

Fig. 35 is a view similar to Fig. 33 with the cloth plate removed to show the arrangement of the feed wheel;

Fig. 36 is a view similar to Fig. 34 with the feed wheel in the position which it occupies after completing one-eighth of a revolution;

Fig. 36^a represents a plan view of a buttonhole showing the stitches formed during the one-eighth revolution of the feed wheel;

Fig. 37 is a view similar to Fig. 34 showing the position of the parts after the feed 40 wheel has completed one-fourth of its revolution and preparatory to the formation of the eye;

Fig. 37^a shows a buttonhole with one side edge thereof completed ready for the formation of the eye;

Fig. 38 is a view similar to Fig. 34 showing the position of the parts during the formation of the first half of the eye of the buttonhole;

Fig. 39 shows a similar view to Fig. 38 with the cloth clamp in position;

Fig. 39^a is a detail plan view of the buttonhole with one-half thereof completed;

Fig. 40 is a plan view with the clamp 55 moved, showing the parts in the position assumed on the completion of the eye of the buttonhole;

Fig. 40^a shows the buttonhole with one side thereof and the eye completed;

Fig. 41 is a plan view with the clamp applied and the parts in the position assumed during the formation of the first half of the second straight stretch of the buttonhole;

Fig. 41^a shows the buttonhole three-fourths 65 completed;

Fig. 42 is a view similar to Fig. 41 showing the parts in the position assumed when the buttonhole is nearing completion;

Fig. 43 is a similar view showing the parts in the position assumed on the completion 70 of the buttonhole;

Fig. 43^a shows a completed buttonhole;

Fig. 44 shows a plan view of the feed wheel;

Fig. 45 is a top plan of the work table 75 with the parts in section;

Fig. 46 is a transverse vertical section on an enlarged scale showing more particularly the pivotal arrangement of the feed wheel, the cutting die and the cloth clamp, the latter being in the position assumed ready for the cutting of the buttonhole;

Fig. 47 shows a fragmentary transverse section with the cutting mechanism in operative position for forming the buttonhole;

Fig. 48 is a view similar to Fig. 46 with the cloth clamp moved forward ready for the initial step in the formation of the buttonhole;

Fig. 49 is an enlarged detail vertical section showing the friction engaging devices of the operating means for the tension device;

Fig. 50 is a detail fragmentary vertical section of a portion of the work table, 95 showing more particularly the arrangement of the stitch setting finger;

Fig. 51 is a detail transverse section on the line 51—51 of Fig. 24;

Fig. 52 is a detail transverse vertical section on the line 52—52 of Fig. 24.

In the embodiment illustrated this improved machine is shown mounted in a supporting structure comprising angle iron standards 2 connected by cross bars 1 and 105 preferably formed integral therewith, a work table 3 being supported on the upper ends of said standards.

Duplicate needle operating mechanisms are shown arranged above and below the work table 3 the construction of which is exactly alike and hence the upper mechanism only will be described in detail. The upper mechanism is mounted in a hollow L-shaped bracket or arm 4 such as is usually employed in machines of this character having a head 5 cast upon one end of the horizontal member thereof. A driving shaft 6 is mounted in bearings carried by the upright member of the arm 4 and extends into said arm being provided on its inner end with a bevel gear 7 and on its outer end with a driving wheel 8, which latter projects outside the arm 4 and whereby motion is imparted to the shaft 6 from any 115 suitable source (not shown).

A vertical cam shaft 9 extends into the hollow upright member of the arm 4 and passes through the table 3 vertically across the supporting structure and is mounted at 130

its lower end in a suitable bearing 10 carried by the base plate 1. This cam shaft 9 has a bevel gear 11 fixed thereto in position to mesh with the gear 7 on the driving shaft 6 and by means of which rotary motion is imparted from the driving shaft to the cam shaft. This cam shaft 9 has keyed thereto a plurality of cams for actuating the various mechanisms of the machine as will be 10 hereinafter more fully described.

Needle operating mechanism.

The machine embodying these improvements has a needle 12 which is designed to 15 carry the thread T which is supplied in lengths sufficient to form one buttonhole only. This needle is alternately transferred from one needle bar 13 to the other, two of which are employed and are adapted to 20 move toward and away from each other as will be presently described. The needle bars are mounted in similarly constructed 25 rocking or vibrating frames 14 which are exactly alike and hence one only will be described. Each needle bar frame 14 is connected at one side to the head of each bracket 30 arm of the machine by pivots 15 and 16 which are preferably cone-pointed screws tapped into said bracket arm so that any 35 wear may be readily taken up. A connecting rod 17 is pivoted at one end to the free 40 side of the frame 14 and has a slot and pin connection at its other end with one arm of a bell crank 18 which is fulcrumed at 19 to 45 the machine arm. This slot and pin connection provides for varying the rocking motion 50 of the needle bar frame. The free arm 20 of the bell crank carries a roller 21 which operates in a cam groove 22 in a needle oscillating cam 23 fixed to the upper end of the 55 cam shaft 9 by means of which the necessary rocking or vibrating motion is imparted to the needle bar frame 14. As the cam shaft 9 rotates the form of the cam 60 groove 22 is such that the bell crank 18 will receive an intermittent rocking motion 65 which will be communicated through the connecting rod 17 to the needle bar frame 14 which turning on its pivots will be 70 rocked, carrying with it the needle bar 13.

The connecting rod 17 is preferably equipped with a turnbuckle 24 for varying the length of said rod.

The needle bars receive their vertical motion from a barrel cam 25 fixed to the cam shaft 9, said cam being here shown mounted on the lower end of said shaft. Levers 26 and 27 are fulcrumed at their rear ends to the horizontally disposed members of the 65 bracket arms of the machine and the front ends thereof are connected by links 28 with laterally extending ears 29 carried by blocks 30 mounted on the needle bars 13. These levers 26 and 27 are mounted within the horizontal bracket arms of the machine and

the fulcrums 32 and 32' thereof extend through one side wall of said bracket arms as is shown clearly in Figs. 3, 5 and 6, bearing sleeves 31 being shown projecting from said bracket arms to support said lever fulcrums. 70

Fixed to the outer end of the fulcrum 32 outside the bracket arm is a rearwardly extending lever arm 33 which projects in a direction opposite to the lever 26 forming an 75 offset continuation of said lever and to which the upper end of a pitman 34 is connected. An arm 35 extends forwardly from the fulcrum 32' of the lever 27 (see Fig. 5) and is connected at its front end with the 80 lower end of pitman 34. Another arm 36 extends rearwardly from said fulcrum 32' of the lever 27 and is offset inwardly and provided at its free end with a roller 37, working in the cam groove 25' of the cam 25 85 carried by the lower end of the cam shaft 9 as is shown clearly in Figs. 2 and 5. The pitman 34 is preferably made in sections connected by a turn buckle 38 to provide for varying the length thereof. 90

It will thus be seen that when motion is imparted to the cam 25 from the driving shaft 6 the roller 37 engaged with the groove 25' thereof will be operated by the cam shape of said groove whereby the lever 27 will be reciprocated vertically and through the pitman 34 will transmit said movement to the lever 26 so that the front ends of both of said levers will be simultaneously moved toward or away from each other for bringing the needle gripping jaws together to provide for the transfer of the needle from one needle bar to the other in a manner hereinafter to be more fully described. 95

Needle transferring mechanism.

Mounted on the inner end of each needle bar 13 is a needle gripping and releasing chuck, the two being exactly alike and hence one only will be described in detail. 100

Extending longitudinally from the inner end of the upper needle bar 13 are two laterally spaced apertured ears 39 and 40 between which the needle gripping jaws 41 and 42 are mounted and which are 110 adapted to move laterally toward and away from each other to grip or release the needle. These jaws 41 and 42 are constructed as shown in Figs. 12 and 13 having rectilinear longitudinally grooved opposed coacting 115 meeting edges 43 and 44 between which the needle 12 is designed to be gripped and held when the jaws are closed. The grooves in these jaws are preferably flared at their lower ends as shown at 43' and 44' to facilitate the reception of the needle. These jaws have laterally extending longitudinally slotted arms 45 and 46 at their upper ends, the arm of jaw 42 being offset outwardly to provide for its overlapping engagement 120 125 130

with the arm of jaw 41 when the jaws are assembled as shown in Fig. 9. The outer edges of these jaws diverge from their front toward their rear ends and are provided on 5 one face with laterally extending lips 47 and 48 designed to slide in upwardly diverging grooves 49 and 50 formed in one side member of a housing 51 carried by the needle bar and mounted to slide thereon and 10 by means of which the opening and closing of the jaws is controlled.

An annular shoulder 52 is formed at the base of the ears 39 and 40 and a coiled spring 53 encircles the needle bar 13 and bears at 15 one end on said shoulder 52 and at its other end against the inner or upper end of the housing 51 whereby said housing is normally held in retracted position as shown in Figs. 8 and 11 and when in this position 20 the jaws 41 and 42 are held in closed gripping relation. As shown this housing 51 is composed of two separable members 54 and 55 which are secured together by suitable fastening screws 56 which also secure in 25 position a cover plate 57 mounted over the front face of the housing to protect the interior thereof from dust and dirt. This housing is preferably keyed to the needle bar 13 as shown in Fig. 14 and is made hollow throughout a portion of its length to receive the ear carrying end of the needle bar and the coil spring 53 mounted thereon as is shown clearly in Figs. 8, 9 and 11. From the above description it will be ob- 30 vious that when the housing is reciprocated on the needle bar 13 that the engagement of the diverging grooves 49 and 50 thereof with the lips 47 and 48 of the needle jaws will operate to open and close said jaws, the 35 jaws being opened when the housing is depressed into the position shown in Fig. 9 and closed when it is raised as shown in Fig. 8.

The means for reciprocating this housing 40 51 is shown in the form of a bell crank 58 which is fulcrumed in a bracket 59 carried by the needle bar 13 and secured thereto by a set screw 60. This bell crank 58 has the free end of its short arm which extends 45 laterally, bifurcated to straddle the housing 51 and the furcations thereof are provided with downturned hooks 61 and 62 which engage laterally extending studs 63 carried by the upper end of the housing 51 50 at opposite sides thereof as is shown clearly in Figs. 7 to 14. The long arm 64 of the bell crank 58 extends upwardly and is provided at its free end with a roller 65 which continuously engages one end of a lever 66. 55 This lever 66 extends into the head 5 of the machine arm 4 and is there secured to a horizontally disposed shaft 67, an opening being provided in said head to provide access to the attachment of said lever 66 with 60 said shaft as is shown clearly in Fig. 1. 65

This shaft 67 is rotatably mounted in suitable bearings on one side of the machine bracket 4 and is provided at its rear end with an inwardly and laterally extending arm 68 which passes into the upright member of said arm 4 and carries at its free end a roller 69 which operates in a cam groove formed in the periphery of a cam 70 fixed to the cam shaft 9 as is shown clearly in Figs. 1, 2 and 6. The cam groove in the 75 cam 70 is so shaped and the movement of the cam is so timed as to move the depending lever 66 inward of predetermined intervals against the roller 65 of the bell crank 58 thereby causing the short hook 80 carrying arm thereof to move downwardly exerting pressure on the housing 51 against the tension of its spring 53, thus opening the needle gripping jaws for releasing the needle which operation occurs when the 85 needle is to be transferred from the upper needle bar to the lower. It is understood that the above described mechanism is duplicated below the work table 3 and that when the gripping jaws above the table open, 90 the lower gripping jaws are simultaneously opened to receive the needle and closed when the needle bars move away from each other.

The needle 12 makes a stroke and has a 95 rest period at each extremity, and in a cycle of operation of the machine the needle reciprocates twice.

The upper needle oscillating cam 23 and the reciprocating cam 25 control the needle 100 bar frame 14 and cause it to move out and back a predetermined distance.

Referring to the lower needle bar and chuck, when the needle bar rises at the beginning of a cycle the chuck begins to open 105 and is completely open when the needle bar has come to rest. It is to be noted that the eye of the needle is near its lower end and is positioned in the lower chuck when it clamps the needle.

Considering the upper needle bar and chuck, as the needle bar descends at the beginning of a cycle, the chuck is completely opened before the needle bar comes to rest and it starts to close before the needle bar 115 comes to rest, and is completely closed after the needle bar comes to rest. The length of time the chuck lever is acting upon the needle chuck should be kept as low as possible so as to keep down the side thrust on 120 the needle bar.

Stitch Forming Mechanism.

The stitch forming mechanism employed herein is similar to that shown in my co-pending application above referred to, the position of the loopers being changed and the operating mechanism therefor altered and controlled by the cam shaft 9.

The peculiar construction and arrange- 130

ment of the stitch forming loopers is shown in Figs. 16 to 22.

This stitch forming mechanism is shown mounted on a bracket 71 secured to and 5 depending from the lower face of the table 3 and having a lateral extension 72 with longitudinally spaced vertical bearings 73 and 74 through which extend pintles 75 and 76 to the lower ends of which are secured links 77 and 78. These links have a slot and pin connection 79 at their inner ends forming a toggle like joint. The link 78 is pivoted intermediately of its ends and is provided on its free outer end with 10 a roller 80 which is disposed in the forked end 81 of an actuating lever 82 and controlled by means to be described.

Two arms 83 and 84 are fixed to the upper ends of the pintles 75 and 76 and are designed to be opened and closed on the opening and closing of the links 77 and 78 for a purpose to be described. These arms 83 and 84 are provided at their free ends with eyes 85 and 86 respectively which are closed 20 by spring tongues 87 and 88 secured at one end to said arms and at the inner side of said eyes and with their free ends extending outwardly and closing the eyes at the terminals of these arms, said terminals 25 being here shown hook-shaped or diverging away from each other and the arms are so mounted that when in closed position, the free end of one overlaps the free end of the other to position the eyes thereof in vertical 30 alinement.

A triangular plate 88 is provided at one end with an apertured arm 89 and is secured to the upper face of the arm 83 being pivotally connected therewith as is shown 40 clearly in Figs. 16 and 17. This plate 88 is in the form of a scalene triangle and is provided with an eye 90 closed by a spring tongue 91, said eye being adapted to register with the eyes on the arms 83 and 84 45 when the loopers or jaws formed by the arms 83 and 84 and the plate 88 are closed, the eyes of these three members being in vertical alinement for the passage of the needle as will be hereinafter more fully described. A substantially right angular link 92 is pivoted at one end to the arm 84 at a point nearer the pivoted end of said arm and the other end of the link is pivotally connected with the plate 88 at a point adjacent the eye thereof with the elbow or angle of the link extending inwardly, said link being so positioned and proportioned that when the arms 83 and 84 are open to their full extent as shown in Fig. 17, a triangular space will be formed between the three eyes of the arms and said plate, said eyes being designed to carry the thread which forms the stitch.

The lever 82 is fulcrumed intermediately 60 of its length on a stud 93 depending from

the table 3 as is shown clearly in Figs. 1 and 24. The rear end of this lever is curved laterally and provided with an upstanding roller 94 on its terminal positioned to engage the periphery of a cam 100 fixed 70 to the cam shaft 9 and shown arranged below the table 3. This roller 94 is held in yielding engagement with the periphery of the cam 100 by means of a coiled spring 82' secured at one end to said lever 82 in 75 advance of its fulcrum and at its other end to the supporting frame. The cam 100 is also provided on its lower face with a cam groove 100' for a purpose to be described.

From the above description it will be 80 seen that on the turning of the cam shaft 9, the cam 22 will be operated for opening and closing the needle bar frames 14 and the cam 100 will operate simultaneously for opening and closing the stitch forming 85 looper jaws so that when the frames 14 are swung open, the jaws formed by the arms and plates above described will be closed and vice versa. By this arrangement the jaws will be held in closed position with 90 the eyes thereof in vertical alinement when the needle bar carrying frames are closed thereby positioning the needle in alinement with the eyes of said looper jaws to adapt it to pass therethrough when forming the 95 stitch, as is shown clearly in Figs. 2, 16, 18, 28 and 29.

When the two needle bars move toward each other the needle 12 carrying the thread approaches and passes upwardly through 100 the registering eyes of the jaws of the stitch forming mechanism, the swinging needle bar carrying frames 14 being in closed position and the thread passes through said eyes and the needle is transferred from the 105 lower to the upper bar as shown in Fig. 29. The continued turning of the shaft 9 causes the wider portion of the cam 100 to engage the roller 94 and the lower portion of the cam 23 to engage the roller 21 connected 110 with the needle bar carrying frames thereby opening the stitch forming jaws and moving the needle bar laterally to position the needle over the cloth C ready to be passed down therethrough into the position 115 shown in Fig. 30. This opening of the jaws forms a triangular loop L in the thread ready for the passage of the needle therethrough. The loop carrying jaws and needle bar frames 14 remain in this position during the passage of the needle through the cloth until after it has passed down through the triangular loop L formed between the eyes of the jaws as is shown in Fig. 31 when said needle is transferred to 120 the lower needle bar. The continued turning of the shaft 9 and the cams 23 and 100 carried thereby gradually closes the loop carrying jaws and the frames 14 thereby lowering the needle and positioning the 125 130

overlapping eyes of the jaws in vertical alignment ready for the next upward passage of the needle.

5 *Stitch tightening and thread tensioning mechanism.*

Just before the looper fingers or jaws are completely closed and after the needle carrying the thread has passed downward 10 through the loop held by said fingers, a stitch tightener 95 operates to draw or cast off the stitch loop from the looper eyes, by grasping the thread which is passed through the loop and sweeping it with the stitch 15 formed therein off said fingers, disengaging it therefrom by forcing it out of the spring closed eyes thereof. The fingers, under the action of the cam 100 then, immediately close as shown in Fig. 32. The continued 20 outward sweep of the tightener 95 exerts a pulling action on the thread T tightening up the stitch as shown in Fig. 32 forming the twisted stitch of the ordinary hand made buttonhole type. As shown in Fig. 32 the 25 tightener acts on that portion of the thread between the new stitch and the needle when in the lower check or clamp. Simultaneously with the tightening of the stitch the thread T is inserted between the jaws of a 30 thread holding and tensioning device to be described. (See Fig. 32.)

After the stitch has been tightened to properly position it in relation to the other stitches of the buttonhole, the tightener 95 35 moves back into normal position, as shown in Figs. 24, 25 and 31 ready for the next operation, the needle being lowered and held by the lower needle bar ready for the next stitch. This operation is continuously 40 repeated until the desired number of stitches have been formed. This improved stitch tightening and thread tensioning mechanism will now be described in detail. The tightening device comprises an arm 96 pivotally mounted at one end on a vertical stub shaft 97 which is supported by a bearing 98 depending from the table 3 at the rear of the machine and by a lateral arm 99 on a depending bracket 101. 45 A friction disk 102 preferably of leather is secured to the lower face of the pivoted end of said arm 96 and contacts with a co-acting disk 103 carried by the upper face of a pinion 104 made integral with the stub shaft and by means of which motion is 50 imparted to the arm 96 as will be presently described. A coil spring 105 encircles the shaft 97 and bears at one end on arm 96 and at its other end against a washer 106 above 55 which a nut 106' is arranged for varying the tension of the spring and thus controlling the frictional contact of the disks 102 and 103 for a purpose to be described.

The arm 96 has a bend or elbow 96' there-

in to avoid interference with the cam shaft 65 9 and the free end of said arm is offset inwardly to position it for engagement with the loopers (see Figs. 1 and 25).

Parallel hooked fingers 107 and 107' extend longitudinally from the free end of arm 96 and are spaced vertically apart a sufficient distance to enable them to pass over the overlapping looper jaws or fingers and to be normally positioned at the rear of said loopers as shown in Figs. 24, 25, and 75 31 ready for the outward sweeping thereof to remove the loop from the loopers and tighten the stitch in the manner above described. A buffer 96^a is positioned for cushioning the return movement of arm 96 (see 80 Fig. 25).

The operating means for this stitch tightening arm consists of a horizontally disposed sector-shaped segment 108 pivotally mounted at its smaller end on a depending 85 stub shaft 108' and having radial teeth on its larger curved free end which mesh with the pinion 104 and which impart motion to said pinion. An actuating roller 109 depends from the lower face of segment 108 and engages a cam groove 110 in the upper face of a cam 400 fixed to the cam shaft 9 and which receives its motion therefrom.

It will thus be seen that the turning of the cam 400 will swing the segment 108 back and forth and thereby oscillate the arm 96 owing to its frictional engagement with the friction disk 103 of the pinion. The engagement of these disks while sufficient to swing arm 96 must not be greater than the strength of the thread as the length of the thread limits the outward sweep of said arm as shown in Figs. 28 to 30 and when held by the thread against further outward movement the friction disks will slide on each other under the action of the segment 108 without effecting any further outward movement of the arm.

The thread tensioning device with which said tightener coacts comprises a pair of 110 long arcuate spring arms 111 and 112, preferably in the form of heavy wires which normally contact throughout their length and are secured together at one end and to a supporting bracket 113 which depends from the table 3. This bracket 113 has a rigid laterally extending curved arm 114 which carries the inner end of the arm 112 and reinforces and braces it.

These arms have their free ends diverging 115 to form a thread receiving mouth 115 which is positioned opposite and adjacent the loopers to adapt said arms to receive the thread between them when the stitch tightener 96 sweeps outwardly as shown in Figs. 28 to 32 so that the thread will be held out of the way to prevent its becoming entangled. The gripping action of the arms is

sufficient to retain the thread comparatively taut without danger of breaking it or pulling it out of the needle eye. To facilitate its release when the needle proceeds on its 5 upward stroke for making another stitch, a cam actuated release rod 116 is provided. This rod 116 is mounted to slide in suitable guides 117 carried by the lower face of the table 3 in a plane substantially at right angles to said arms 111 and 112. One end of 10 this rod 116 is positioned to align with a screw 118 adjustably carried by an upstanding arm 119 of a plate 120 fixed to the outer face of the outer arm 111. The inner end 15 of this rod 116 is offset downwardly and provided with a roller 121 which engages a groove 122 in a cam 300 fixed to the cam shaft 9 and by means of which the rod is projected and retracted to bring it into or 20 out of engagement with the screw 119. The projection of rod 116 by cam 300 causes its free front end to engage screw 119 and force the jaw 111 away from the jaw 112 and relieve the tension on the thread sufficiently 25 to permit it to be drawn easily through the looper fingers and to prevent the loose end of the thread from being pulled through the needle eye. The groove 122 of cam 300 is so shaped and proportioned as to release the 30 tension on the thread just at the time when the upper needle bar starts up carrying the threaded needle.

Spring pressed studs 123 arranged on the outer face of the jaw 111 of the tension device serve to hold the jaws in yielding engagement. (See Figs. 24, 25 and 52.)

The looper finger controlling cam 100, which also controls the cloth feed to be described, is so constructed as to cause the fingers to begin closing immediately after the needle has passed through them and said fingers are nearly closed on the beginning of the outward movement of the thread tension or tightening arm 96.

45 The stroke of cam 400 is sufficient to permit the tension or stitch tightener arm 96 to have a slightly longer throw than is necessary. This arm 96 begins to move out before the end of the stroke of the lower 50 needle bar and is back again after beginning of the next stroke of the lower needle bar, producing quite a quick motion of the arm.

If found desirable the movement of this arm may be accelerated and the rest period 55 at the end of its outward stroke prolonged to provide for a slower and better action of the stitch setting finger to be described.

Stitch setting mechanism.

60 During the entire stitching of the buttonhole the engagement of the thread by the tightener 95 exerts a pull on the stitch lengthwise of the buttonhole instead of transversely thereof or at right angles to

the edge which is the direction in which the 65 stitch is to be formed and hence it becomes necessary to provide means for overcoming this lengthwise pulling of the tightener.

The device shown (see Figs. 24 and 25) for this purpose comprises an upstanding 70 finger 124 which rises from an arm 125 engaged by the forked end of one arm 126 of a lever fulcrumed intermediately of its ends on a stud 127 depending from the table 3 at the front end thereof (see Fig. 2). The 75 other arm 128 of this lever is offset downwardly and has its free end pivotally connected with an actuating rod 129 which extends longitudinally toward the rear of the machine and is pivoted to an arm 130 provided with an upstanding roller 131 which operates in and is controlled by a groove 201 in what may be termed the stitch setting cam 200. Arm 130 is pivoted at one end to a stud depending from table 3 as 80 seen in Fig. 25. The action of the finger 124 as shown in Fig. 28 is to pull the thread into the proper position relative to the buttonhole against the tension exerted on the thread by the arm 96 thereby setting the 85 stitch and holding the thread in proper relation to the needle and preventing a miss-stitch. This finger 124 under the action of cam 200 begins moving over to set the stitch just as soon as the arm 96 will permit and 90 operates in connection with every stitch formed. Arm 125 slides in stationary 95 guide 125^a as seen in Fig. 50.

Cloth clamping and feeding mechanism. 100

In making a buttonhole the goods after being clamped by a cloth clamp 135 such as is shown and described in Patent #319,700 to Greene dated June 9, 1885, has the hole H cut therein by means to be described and the clamp is placed over and engaged with a cloth plate 136. This plate is similar to the plate shown and described in Patent 272,126 to Diehl dated February 13, 1883, except that the slot 137 in this case is reversed, the curved intermediate portion thereof extending toward the left instead of toward the right. After being so clamped the goods is stretched relative to the buttonhole to separate the walls of the 110 slit. After being stretched the goods is moved automatically to present it in the proper position for each successive stitch. This clamp is secured to the plate 136 by a button 139 rising from plate 136 and working in the slot s of the clamp (see Fig. 46) and has an overhanging head 140 engaging the upper face of the clamp on opposite sides of the slot s. The clamp is held in position against the button by a spring 120 pressed finger 141, and the button has a slot 139^a extending transversely relative to the cloth plate and which is designed to permit

the needle 12 to shift laterally during the formation of the stitch.

The clamp is driven by means of a pin 135' which projects from its lower face, 5 passes through the slot 137 in the cloth plate 136 and enters a driving groove 143 in the upper face of the feed wheel 144.

In order to produce a properly made buttonhole by this mechanism it is necessary 10 to communicate to the clamp pin 135' as it travels along the straight portion of said slot a regular intermittent motion of the same extent as the space required between the stitches. Upon entering the curved part 15 of the groove, however, the diameter of such curve being so much greater than that of the eyelet to be stitched, it is obvious that the extent of these intermittent movements of the pin must be very greatly increased. 20 For this purpose it is necessary to communicate to the feed wheel 144 by which said pin is driven, a regular intermittent rotary motion, which, at the proper point and during the period required for stitching the 25 eyelet shall be automatically increased, and which shall automatically return to a slower speed when it commences to stitch the straight part of the buttonhole.

30 *Feed wheel actuating mechanism.*

The mechanism for actuating the feed wheel 144 is similar to that described and shown in Patent 272,126 to Diehl above referred to and comprises a driving lever 145 (see Figs. 23 and 24), which is pivoted to the bed of the machine at 146 and provided with an arm 147 extending toward the feed wheel 144, the other arm of said lever extending rearwardly and being provided with 40 a roller 148 which operates in a cam groove 100' formed in the lower face of the looper operating cam 100, and by the revolution of which a regular rocking motion is communicated to the driving lever 145. The arm 45 147 of this lever carries adjustable blocks 150 and 151 which are designed to be engaged by a shipper lever 152. This shipper lever is provided with a roller 153 which works in a groove 154 in the lower face of 50 the feed wheel 144 and is also pivoted as shown at 155 to the feed lever 156. This feed lever 156 is provided with a block 157 which fits in and works in a feed groove 158 of the feed wheel 144. When one of the 55 blocks 150 or 151 of the driving lever 145 rocks against the shipper lever 152 the roller 153 will act for the moment as a fulcrum point for said shipper lever and the feed lever 156 will be so moved as to first cramp 60 the block 157 in the groove 158 of the feed wheel 144 and then to move it and with it the feed wheel making one forward step of the feed. On the return movement of the driving lever 145 when its arm 147 moves

away from the arm of the shipper lever, the 65 block 157 is no longer cramped in the groove and as soon as it is relieved, is drawn back carrying with it the feed and shipper levers so as to be ready for the next movement. This drawing back is accomplished by means 70 of a spiral spring 159 one end of which is attached to the block carrying end of the feed lever and the other to a point outside of the feed wheel.

The two adjustable blocks 150 and 151 75 which are shown carried by the driving lever 145, but may be carried by the shipper lever if found desirable, are designed for varying the extent of the feed motion communicated to the feed wheel at the proper points 80 when employed in connection with the cam groove 154 in which the roller 153 operates. This groove is made of such a form that during that portion of the revolution of the feed wheel when small movement is required, the block 151 will be thrown in contact with the shipper lever, but as soon as the point is reached where the larger movement is required the position of the roller 153 will be changed relatively to the pivot 85 155 and the shipper lever will be so shifted that the block 150 only will come in contact therewith. As the block 150 is nearer the fulcrum of the driving lever and farther from the point where the shipper lever is 90 pivoted to the feed lever, it is obvious that during its contact, a relatively small motion will be communicated to the feed and it is also evident that when the block 151 is 95 thrown into action, its point of contact being farther from the fulcrum of the driving lever and nearer said pivot connecting the shipper and feed levers, the amount of motion communicated to the feed wheel will be 100 very largely increased. Each of the blocks 105 150 and 151 is attached to the driving lever by a set screw passing through a slot and can therefore be adjusted so as to still further vary the extent of both the greater and smaller motions or to vary either without 110 affecting the other.

From the above description it will be obvious that a regular intermittent rotary motion will be communicated at the proper points and during the period required for 115 stitching the eyelet or buttonhole, and this motion will be automatically increased and returned to a slower speed for stitching the straight part of the buttonhole as will be presently described.

In the operation of this machine the cloth is first placed in the clamp as shown in Fig. 46 with the clamping pin 135' thereof engaged with the long arm 137^a of the slot 137 in the cloth plate 136 whereby the 125 cloth is properly positioned for the cutting of the buttonhole H by mechanism herein-after to be described. The cloth has pref-

erably marked thereon by chalk or otherwise the points at which the buttonholes are to be formed so as to enable the operator to properly position the cloth relative to the cutter.

5 After the buttonhole H has been cut and it is in the form shown in Fig. 33^a the clamp is moved forward in the slot 137^a across the opening 169 in the table and the pin 135' rides up the inclined wall 169' onto the

10 upper face of feed wheel 144 and drops into the groove 143 thereof as shown in Fig. 48. The front end of the slit of the buttonhole opposite to the eye end thereof is then positioned directly beneath the needle 12 of the machine as indicated in Figs. 33 and 34. The machine is then set in motion and as the feed wheel revolves from left to right the pin 135' carrying with it the clamp 135 is compelled to move intermittently in the direction of the straight arm 137^a of the slot 137 in the cloth plate 136, the stitch being formed in the manner hereinbefore described and as shown clearly in Fig. 36^a. When the pin 135' of the clamp reaches the position shown in Fig. 36 the feed wheel will have completed one-eighth of a revolution and one-half of the first straight stretch of the buttonhole will have been formed as is shown in Fig. 36^a. When the pin 135' reaches the

25 curved part 137^b of the slot 137 as shown in Fig. 37, the feed wheel will have completed one-fourth of its revolution and one side edge of the buttonhole will have been completed ready for the formation of the eye as

30 shown in Fig. 37^a. At this point the pin is encountered by a dog 160 which rides out of the recess 161 (see Fig. 35) in which it has been housed during the operations above described. This dog which is carried by the

35 feed wheel 144 engages the pin and carries it with it around the curved portion 137^b of the slot 137 in the cloth plate until it reaches the end of said curve and during which time the eyelet of the buttonhole has been stitched as shown in Figs. 40 and 40^a. This action of the dog causes the clamping plate to revolve into the position shown in Fig. 41 ready for the formation of the other straight stretch of the buttonhole. Fig. 39 shows the position the clamp assumes when one-half of the buttonhole has been completed as shown in Fig. 39^a, Fig. 40 showing the position the clamp assumes on the completion of the eyelet as shown in Fig. 40^a.

40 After the clamp has been turned from the position shown in Fig. 33 to the position shown in Fig. 41 one side of the buttonhole and the eye have been completed and the parts are ready for the formation of the second straight stretch of the buttonhole. The dog 160 now leaves the groove 143 and said groove acting on the pin 135' forces it to travel along the other straight portion 137^c of the slot 137 until the other straight

stretch of the buttonhole is stitched and the 65 buttonhole completed as shown in Figs. 43 and 43^a.

Just before the completion of the buttonhole the power operating the machine is cut off to prevent the momentum of the machine 70 from producing additional stitches at the end of the buttonhole and should it be found necessary to form an additional stitch or two after the power has been so cut off the feed wheel may be revolved a step or two by actuating a hand lever 162 shown at the left of Fig. 35 which carries a spring pressed dog 163 engaged with the teeth of the feed wheel 144 and by means of which said motion is imparted without danger of too many 80 stitches being formed.

Buttonhole cutting mechanism.

The buttonhole cutting mechanism preferably employed is essentially the same as is 85 fully shown and described in U. S. Patent No. 322,428, dated July 21, 1885, the method of operation being slightly different.

This mechanism briefly stated comprises a spring actuated weighted cutter carrying 90 lever 165 fulcrumed on the work table 3 and having a link connection with a rock shaft 166 mounted in brackets depending from the table. A pivoted arm 167 (see Fig. 47) is arranged beneath the work table 95 3 and carries a cutting die 168 which cooperates with the cutter of lever 165. This die 168 is forced upward through an opening 169 in the table as the cutter carrying lever 165 descends, by a mutilated V-shaped 100 member 170 fixed at its apex to the rock shaft 166. This die supporting and raising member 170 has one arm longer than the other and the free end of the long arm 172 is connected with the arm 167 between the 105 die 168 and its pivot, by links 173 one end of each of which is pivoted to said arm and the other has a slot and pin connection with the long arm 172 of the V-shaped member 170. Normally the short arm 174 engages 110 the die carrying end of arm 167 as shown in Figs. 46 and 47 but when lever 165 is depressed, the shaft 166 is rocked and the end of the long arm 172 forced under said die carrying arm 167 thereby elevating said 115 arm and projecting the die into the table opening 169 said long arm serving to support the die in this position and to take the thrust caused by the descent of the lever 165. (See Fig. 47).

120 The rock shaft 166 extends longitudinally under the work table and is supported in suitable bearings depending from said table. A link 171 connects an arm on the rear end of this shaft with the rear end of 125 the weighted cutting lever 165 which is fulcrumed on the work table at one side of the upright bracket arm thereof as shown

in Fig. 1. A coiled spring 174 encircles the fulcrum of this lever and has one end engaged with said lever and its other end engaged with a ratchet wheel 175 revolvably mounted on said fulcrum and held by a pawl 176 and by means of which the tension of the spring may be varied to control the resistance of the lever 165 which is held raised by said spring and returned to raised position thereby after it has been actuated to cut a buttonhole.

In the use of this cutter the parts being in the position shown in Figs. 1 and 46, the operator grasps the lever 165 and forces it downwardly and this movement of said lever through its link connection with shaft 166 rocks said shaft and rotates arm 172 causing it to pass under the die carrying arm 167 and force the die 168 upward into the position shown in Fig. 47 where it meets the knife on lever 165 and coöperates therewith to cut the buttonhole. Immediately lever 165 is released the spring 174 lifts it to inoperative out-of-the-way position and simultaneously the die 168 is lowered by the rocking of shaft 166 and the parts so remain until another buttonhole is to be cut.

I claim as my invention:

30 1. In a buttonhole sewing machine, the combination of a supporting structure, a needle, two needle gripping and transferring devices movable toward and away from each other and between which the material is fed, levers fulcrumed on said structure, connections between the front ends of said levers and said devices, a pitman connecting the rear end of one of said levers with the other lever between its fulcrum and front 40 end, said last mentioned lever having a roller on its rear end, a revoluble cam engaged with said roller, and means for operating said cam.

45 2. A buttonhole sewing machine including in combination, a needle, needle gripping and transferring devices movable toward and away from each other and between which the material is fed, mechanism for forming a loop encircling the path of movement of said needle, a thread tension device, means for tightening said loop and positioning it in said tension device, means for relieving the tension on the thread at the beginning of the stitch, and a stitch setting 50 device coöperating with said tightening means.

60 3. A buttonhole sewing machine, including in combination, a needle, needle gripping and transferring devices movable toward and away from each other and between which the material is fed, mechanism for forming a loop encircling the path of movement of said needle, a thread tension device, and means for tightening said loop

and positioning the thread in said tension device.

4. A buttonhole sewing machine, including in combination, a needle, needle gripping and transferring devices movable toward and away from each other and between which the material is fed, mechanism for forming a loop encircling the path of movement of said needle, a thread tension device, means for tightening said loop and positioning the thread in said tension device, 70 and means for relieving the tension on the thread at the beginning of a stitch.

5. A buttonhole sewing machine, including in combination a needle, needle gripping and transferring devices, movable toward and away from each other and between which the material is fed, mechanism for forming a loop encircling the path of movement of said needle, a thread tension device, means for tightening said loop and 80 positioning the thread in said tension device, and cam controlled means for relieving the tension on the thread at the beginning of a stitch.

6. A buttonhole sewing machine, including in combination, a needle, needle gripping and transferring devices movable toward and away from each other and between which the material is fed, mechanism for forming a loop encircling the path of 90 movement of said needle, a thread tension device, means for tightening said loop and positioning the thread in said tension device, said tightening means including a swinging arm, and means for actuating said 95 tightener arm and for returning it to normal position.

7. A buttonhole sewing machine, including in combination, a needle, needle gripping and transferring devices movable toward and away from each other and between which the material is fed, mechanism for forming a loop encircling the path of movement of said needle, a thread tension device, a loop tightener for positioning the 105 thread in said tension device, means for actuating said tightener and for returning it to normal position, said actuating means including a yieldable connection for permitting the tightener to move relatively to 110 its actuating means when a predetermined resisting force is brought to bear on said tightener.

8. A buttonhole sewing machine, including in combination, a needle, needle gripping and transferring devices movable toward and away from each other and between which the material is fed, mechanism for forming a loop encircling the path of movement of said needle, a thread tension device, means for tightening said loop and positioning the thread in said tension device, cam controlled means for actuating said 120

tightener and for returning it to normal position, said tightener actuating means having engaging friction faces operable to move the tightener simultaneously with said actuating means under normal conditions, said actuating means being movable independently of the tightener when a predetermined force is brought to bear on said tightener.

10 9. A buttonhole sewing machine, including in combination, a needle, needle gripping and transferring devices movable toward and away from each other and between which the material is fed, mechanism for 15 forming a loop encircling the path of movement of said needle, a thread tension device, a yieldable swinging arm for tightening said loop and positioning the thread in said tension device, means for actuating said 20 tightener and for returning it to normal position, and a stitch setting device operated in timed relation to the tightening arm.

10 10. A buttonhole sewing machine, including in combination, a needle having an eye 25 near one end, needle gripping and transferring devices movable toward and away from each other and between which the material is fed, one of the needle gripping devices being adapted to receive the needle eye, 30 mechanism for forming a loop encircling the path of movement of said needle, a thread tension device, and means for tightening said loop and positioning the thread in said tension device, the positioning of the thread 35 in the tension device by the tightener being controlled by the length of the thread between the stitch last formed and the needle.

11. A buttonhole sewing machine including an oscillating stitch tightening arm having spaced thread engaging fingers, and a thread tensioning device arranged in substantially the same plane as said arm and having yieldable thread clamping jaws adapted to enter between the fingers of said 45 arm when the arm is swung outward into thread tightening position and to receive and hold the thread under tension.

12. A stitch tightener for buttonhole sewing machines including an arm having a 50 pair of longitudinally extending spaced thread engaging fingers with hooks at their free ends, oscillating means for said arm comprising a shaft with which the other end of said arm is loosely engaged, a fixed 55 pinion carried by said shaft, a cam controlled actuating gear meshing with said pinion, friction disks carried by the opposed faces of said pinion and arm and contacting with each other whereby motion is imparted to said arm, and means for causing the frictional engagement of said disks.

13. A stitch tightener for buttonhole sewing machines including an arm having a 60 pair of longitudinally extending spaced

thread engaging fingers with hooks at their 65 free ends, oscillating means for said arm comprising a shaft with which the other end of said arm is loosely engaged, a fixed pinion carried by said shaft, a cam controlled actuating gear meshing with said 70 pinion, friction disks carried by the opposed faces of said pinion and arm and contacting with each other, whereby motion is imparted to said arm, a spring forcing said arm into engagement with said pinion, and means 75 for varying the tension of said spring.

14. A thread tensioning device for buttonhole sewing machines comprising a pair of jaws connected at one end and having the terminals of their free ends diverging, said 80 jaws normally contacting throughout their length, spring means for holding said jaws in yieldable engagement and means for separating said jaws at predetermined intervals.

15. A thread tensioning device for buttonhole sewing machines comprising a pair of jaws connected at one end and having the terminals of their free ends diverging, said 90 jaws normally contacting throughout their length, spring means for holding said jaws in yieldable engagement, a bracket carried by one of said jaws and having a pin extending in a plane transversely thereof, a push rod disposed in alignment with said 95 pin and normally out of contact therewith, and means for projecting said rod at intervals to cause it to engage said pin and separate said jaws.

16. A thread tensioning device for buttonhole sewing machines comprising a pair of jaws connected at one end and having the terminals of their free ends diverging, said 100 jaws normally contacting throughout their length, spring means for holding said jaws in yieldable engagement, a slidably mounted push rod, and a member carried by one of said jaws and positioned in the path of said rod whereby the jaws are opened on the movement of said rod in one direction.

17. A buttonhole sewing machine including a needle bar, a pair of needle clamping jaws mounted on one end of said bar and both of which are movable toward and from the longitudinal axis of said bar, a slide on the bar for actuating said jaws simultaneously toward and from each other, a spring for moving the slide in one direction and means for moving the slide in the opposite direction.

18. A buttonhole sewing machine, including a needle bar, a transverse pin at one end of said bar, a pair of needle clamping jaws projecting longitudinally from the needle bar and having slotted portions slidable on said pin and both being movable toward and from the longitudinal axis of said bar, a slide on the needle bar, said slide and jaws

- having coöperating elements to cause the latter to slide laterally simultaneously upon the reciprocation of the slide and means for operating said slide.
- 5 19. A buttonhole sewing machine including a needle bar, a needle chuck carried thereby and comprising a pair of laterally movable jaws having coacting needle gripping faces, and a member slidable on said
- 10 needle bar, said member and jaws, one having diverging grooves and the other diverging lips engaging said grooves whereby said jaws are opened and closed on the reciprocation of said member on said needle bar.
- 15 20. A buttonhole sewing machine including a needle bar, a needle chuck carried thereby and comprising a pair of laterally movable jaws extending longitudinally therefrom and having laterally extending
- 20 slotted arms, a pin extending through the slots in said arms and connecting said jaws to said needle bar, one of said arms being offset to provide for their overlapping connection, said jaws having their outer faces
- 25 diverging rearwardly and provided with laterally extending lips, a jaw actuating member slidable on said needle bar and having rearwardly diverging grooves to receive said lips, and means for reciprocating said
- 30 member for opening and closing said jaws.
21. A buttonhole sewing machine including a needle bar, a needle chuck carried thereby and comprising a pair of laterally movable jaws having coacting needle gripping faces, a member slidable on said needle bar, said member and jaws having coöperating elements for openings and closing said jaws on the reciprocation of said member, reciprocating means for said member comprising a bracket carried by said needle bar, a bell crank mounted in said bracket and having one arm extended horizontally and bifurcated to straddle said member, the furcations of said arm and said member having coöperating engaging elements, a cam controlled shaft having a depending arm in the path of which the other arm of said bell crank is positioned and by means of which said jaw actuating member is moved in one
- 45 direction, and a spring for moving it in the opposite direction.
22. A buttonhole sewing machine, including in combination, a needle, needle gripping and transferring devices movable toward and away from each other and between which the material is fed, mechanism for forming a loop encircling the path of movement of said needle, a thread tension device, means for tightening said loop and positioning the
- 55 thread in said tension device, and stitch setting mechanism for properly positioning the stitch before the tightening of the loop.
- 60 23. A buttonhole sewing machine, including in combination, a needle, needle gripping

and transferring devices movable toward 65 and away from each other and between which the material is fed, mechanism for forming a loop encircling the path of movement of said needle, a thread tension device, means for tightening said loop and positioning the thread in said tension device, and cam controlled stitch setting mechanism for engaging and setting each stitch prior to the tightening of the loop.

70 24. A buttonhole sewing machine, including in combination, a needle, needle gripping and transferring devices movable toward and away from each other and between which the material is fed, mechanism for forming a loop encircling the path of movement of said needle, a thread tension device, means for tightening said loop and positioning the thread in said tension device, a stitch setting finger projectible into engagement with each stitch loop prior to 80 the tightening thereof, and means for actuating said finger.

85 25. A buttonhole sewing machine including a stitch setting mechanism comprising a lever fulcrumed intermediate of its ends 90 and having one end bifurcated, an arm mounted in said bifurcated lever end and having an upstanding stitch engaging finger, an actuating rod pivotally connected with said lever, an arm pivoted to said rod and 95 having an upstanding roller, and a cam having a groove in which said roller operates and by which the stitch setting finger is controlled.

100 26. In a buttonhole sewing machine, a stitch forming mechanism including a pivotally mounted stitch tightener, a slidably mounted stitch setter, said tightener and setter operating in planes substantially at right angles to each other, the tightener exerting a pull on the stitch lengthwise of the buttonhole and the setter exerting a pull transversely of the buttonhole, and means for operating the tightener and the setter in timed relation.

105 27. In a buttonhole sewing machine, a stitch forming mechanism including a stitch tightener, a stitch setter operable to engage and set each stitch in timed relation to the actuation of the tightener, the tightener exerting a pull on the stitch lengthwise of the buttonhole and the setter exerting a pull transversely of the buttonhole, and means for operating the tightener and the setter in timed relation.

110 28. In a buttonhole sewing machine, a thread tension device including a pair of thread holding jaws composed of longitudinally curved resilient metal rods normally in contact with each other throughout their length and one of which is movable toward and from the other, the free ends of the jaws having a flared entrance portion to receive

- the thread, a series of spaced spring devices for forcing the movable jaw toward the other jaw, and means for moving the said movable jaw away from the other jaw at predetermined intervals to release the thread. 5 and between said tension jaws, means for actuating the tension device in timed relation to the needle and loop forming mechanisms, a stitch setting finger operable in timed relation to the stitch tightening device, means for operating said finger, and 65
29. A machine for making a hand button-hole comprising in combination a needle carrying a thread, needle gripping and transferring mechanisms movable toward 70 and away from each other and between which the material is fed, mechanism for forming in said thread a loop encircling the path of the needle as it moves in one direction, a thread tension mechanism for holding the portion of the thread between the needle and the last formed stitch, a stitch setting mechanism, stitch tightening mechanism for moving the loop from the loop forming mechanism and positioning 75 the thread in said tension mechanism, mechanism for holding the material having a buttonhole slit and moving the edge of the slit relative to the path of the needle, and means for shifting the needle operating mechanisms relative to the edge of the buttonhole 80 slit, said mechanisms being movable in timed relation. 85
30. A machine for making a hand button-hole comprising in combination, a needle carrying a thread, needle gripping and transferring mechanisms movable toward and away from each other and between which the material is fed, mechanism for forming in said thread a loop encircling the path of the needle as it moves in one direction, a thread tension mechanism for holding the portion of the thread between the needle and the last formed stitch, stitch tightening mechanism for moving the loop 90 from the loop forming mechanism and positioning the thread in said tension mechanism, mechanism for holding the material having a buttonhole slit and moving the edge of the slit relative to the path of the needle, and means for shifting the needle operating mechanisms relative to the edge of the buttonhole slit, said mechanisms being movable in timed relation. 95
31. A machine for making a hand button-hole comprising in combination, a needle carrying a thread, needle gripping and transferring devices movable toward and away from each other and between which the material is fed, means for reciprocating 100 said devices and shifting them laterally at predetermined intervals, loop forming mechanism including a plurality of needle receiving eyes movable to alined and disaligned positions, means for operating said mechanism in timed relation to the movement of the needle, a pair of thread tension jaws one of which is movable with respect to the other, means for moving said movable jaw in timed relation to the needle operating mechanism, a stitch tightening device to sweep the loop off of the loop forming mechanism and between said tension jaws, means for actuating the tension device in timed relation to the needle and loop forming mechanisms, a stitch setting finger operable in timed relation to the stitch tightening device, means for operating said finger, and means for holding material having a buttonhole slit, and feeding it with respect to the needle. 105
32. A machine for making a hand button-hole comprising in combination, a needle carrying a thread, needle gripping and transferring devices movable toward and away from each other and between which the material is fed, means for reciprocating said devices and shifting them laterally at predetermined intervals, loop forming mechanism including a plurality of needle receiving eyes movable to alined and disaligned positions, means for operating said mechanism in timed relation to the movement of the needle, a pair of thread tension jaws one of which is movable with respect to the other, means for moving said movable jaw in timed relation to the needle operating mechanism, a stitch tightening device to sweep the loop off of the loop forming mechanism and between said tension jaws, means for actuating the tension device in timed relation to the needle and loop forming mechanisms, a stitch setting finger operable in timed relation to the stitch tightening device, means for operating said finger, and means for holding material having a buttonhole slit, and feeding it with respect to the needle. 110
33. In a sewing machine, the combination of a needle having an eye through which the thread slides, needle operating mechanism, mechanism for forming a loop in the needle thread encircling the path of the needle, a thread tension mechanism including a pair of normally contacting thread holding jaws which receive the thread between their free ends and one of which is movable toward and away from the other, a stitch tightening mechanism to sweep the loop from said loop forming mechanism and position the thread between said jaws, and means for operating said mechanisms in timed relation. 115
34. In a sewing machine, the combination of a needle having an eye through which the thread slides, needle operating mechanism, mechanism for forming a loop in the needle thread encircling the path of the needle, a thread tension mechanism including a pair of normally contacting thread holding jaws which receive the thread between their free ends and one of which is movable toward and away from the other, a stitch tightening mechanism to sweep the loop from said loop forming mechanism and position the thread between said jaws, a stitch setting 120

- 60

mechanism including a projectible thread engaging finger, and means for operating said mechanisms in timed relation.

35. In a sewing machine, the combination 5 of a needle having an eye through which the thread slides, needle operating mechanism, mechanism for forming a loop in the needle thread encircling the path of the needle, a thread tension mechanism including a pair 10 of longitudinally curved thread clamping jaws disposed in substantially the same plane as said loop forming mechanism, said jaws normally contacting throughout their length and one of which is movable toward 15 and away from the other, a stitch tighten-

ing mechanism including a swinging arm to work toward and from the loop forming mechanism and over said tension jaws to move the loop from said loop forming mechanism and position the thread between 20 said jaws, and means for operating said mechanisms in timed relation.

In testimony whereof I have hereunto set my hand in the presence of two subscribing witnesses.

JOSEPH FORMAN.
